INVENTOR.

George L. Waitt.

UNITED STATES PATENT OFFICE.

GEORGE L. WAITT, OF PHILADELPHIA, PENNSYLVANIA, ASSIGNOR, BY MESNE ASSIGNMENTS, TO THE GERMANIA BOTTLE COMPANY, OF SAME PLACE.

BOTTLE-STOPPER.

SPECIFICATION forming part of Letters Patent No. 379,919, dated March 20, 1888.

Application filed March 29, 1887. Serial No. 232,909. (No model.)

To all whom it may concern:

Be it known that I, GEORGE L. WAITT, a citizen of the United States, residing in Philadelphia, in the county of Philadelphia and State of Pennsylvania, have invented a certain new and useful Improvement in Bottle-Stoppers, of which the following is a specification sufficient to enable others skilled in the art to make and practice the same.

The present invention relates to that class of bottle-stoppers in which a swinging bail carries the stopper which closes the mouth of the bottle.

The invention consists in the construction and combination of devices hereinafter claimed, whereby I attain great simplicity, cheapness, and ease of operation.

In the accompanying drawings, Figure 1 is a front elevation of a portion of a bottle-neck, 20 showing one form of pivoted locking-lever and the stopper seated on the mouth of the bottle and locked. Fig. 2 is a corresponding view showing another form of locking-lever. Fig. 3 is a side elevation of the construction shown in Fig. 1. Fig. 4 is a side elevation of the construction shown in Figs. 1, 2, and 3, with the stopper thrown back. Fig. 5 is a sectional view of a bottle-neck having two biting-rims for the stopper. Fig. 6 is a detail side view of 25 the stopper holder or cap, the stopper, and the back-stop for the locking-lever. Fig. 7 is a sectional view showing the manner of pivoting and attaching the locking-lever to the stopper-holder.

The reference-numeral 1 designates a portion of a bottle, which, in the present instance, is provided with inner and outer biting-rims, 1^a and 1^b, around the bottle-mouth, as is claimed in my Patent No. 342,051, dated May 18, 1887.

A cap or holder, 2, for the cork or stopper proper (marked 6) is struck up from sheet metal, or it may be made of cast metal, which probably is the preferable mode of formation. The cap is formed with a cavity, which receives a cork or 45 piece of rubber, 6, serving as a stopper, and made large enough to have the biting-rims on the bottle enter the substance of the stopper when the latter is pressed into or upon the bottle-mouth. The metal cap or holder 2 is

formed with a transverse groove or channel, 50 2^a, on its upper surface, which serves as the curved bearing or fulcrum surface for a rocking lever, 3. Furthermore, the top of the cap is formed with a fixed post, 7, which serves as a back-stop for said lever 3. As shown in 55 Figs. 1, 2, and 3, the lever 3 is formed from a piece of wire, which is bent into a loop form, and has an eye, 3^b, formed at the top by properly coiling said wire. The bottom of the loop rests in the groove in the top of the cap, 60 and is held therein by means of a fastening-clasp, 10, made of some ductile or flexible metal. This clasp 10 has an eye at the top, which receives the bottom of the lever 3, and allows the latter to rock or turn in the groove 65 in the cap. The legs of the clasp 10 are passed through a hole, 2^b, made in the top of the cap, and are then bent around or clinched on the under side of said top, as is clearly shown in Fig. 7. It will be seen that the clasp is the 70 medium for attaching the lever 3 to the cap 2, and that the cork or rubber forced or held in the cap will contribute to prevent the unbending of the clinched ends of the clasp.

In Fig. 2 I have shown substantially the 75 same construction as has already been described. In this instance, however, the lever 3 is made of a wire which has a top eye, two vertical legs brought close together, and bent at the bottom to form two journals, 3^a. These 80 journals turn in the groove in the top of the cap 2, and two clasps 10, instead of one, serve to hold the lever in place. A bail or yoke, 4, pivoted or hung on a wire ring, 5, surrounding the neck of the bottle, receives the eye portion of the lever 3, and consequently carries all the movable parts of the stopper-fastening. The bail or yoke 4 swings in the manner common to stopper-fasteners of the "swing-stopper" type, and when the stopper is seated in 90 the bottle-mouth and the lever 3 turned into a vertical position, so as to rest against the back-stop 7, a tight joint will be insured between the stopper and the bottle's mouth. By forcing the lever 3 away from the back-stop by finger-pressure applied in the proper direction, the 95 stopper will be unseated, and the lever and swinging bail can then be swung away from

the bottle in the manner indicated in Fig. 4. As shown more fully in Figs. 3 and 4, the back-stop 7 has a rounded groove, 7^a, which receives the eye 3^b on the swinging bail when 5 the lever is in the upright or locked position.

Having thus described my invention, what I claim as new, and desire to secure by Letters Patent, is—

The combination of the cap 2, having a 10 rounded groove, 2^a, in its top and a slot through the latter, the back stop or post 7, the rocking

lever seated and turning in the groove in the cap 2, and the clasp 10, passed through the slot in the cap and clinched on the under side of the latter, with the cork or stopper 6 and 15 the swinging bail 4, mounted on the bottle-neck, substantially as herein set forth.

GEORGE L. WAITT.

Witnesses:

J. DANIEL EBY,
S. LLOYD WIEGAND.

It is hereby certified that Letters Patent No. 379,919, granted March 20, 1888, upon the application of George L. Waitt, of Philadelphia, Pennsylvania, for an improvement in "Bottle Stoppers," was erroneously issued to the "Germania Bottle Company" as sole owner of the patent; whereas the said letters should have been issued to *S. Lloyd Wiegand, of Philadelphia, Pennsylvania, and said Germania Bottle Company, jointly*, said Wiegand and the Germania Bottle Company being assignees by direct and mesne assignments of the entire interest in said invention as shown by assignments of record in the United States Patent Office; and that the proper correction has been made in the files and records of the case in the Patent Office, and should be read in the Letters Patent that the same may conform thereto.

Signed, countersigned, and sealed this 27th day of March, A. D. 1888.

[SEAL.]

D. L. HAWKINS,
Assistant Secretary of the Interior.
